UNITED STATES PATENT OFFICE

162,795

ELECTRICAL CONNECTOR

Donald R. De Tar, Stratford, Conn., assignor, by
mesne assignments, to Winchester Electronics,
Incorporated, Glenbrook, Conn.

Application June 3, 1949, Serial No. 3,040

Term of patent 14 years

(Cl. D26—1)

To all whom it may concern:

Be it known that I, Donald R. De Tar, a citizen of the United States, residing at 320 Hurd Avenue, Stratford, Connecticut, have invented a new, original, and ornamental Design for Electrical Connector, of which the following is a specification, reference being had to the accompanying drawing, constituting a part hereof:

Fig. 1 is a perspective view of an electrical connector showing my new design.

Fig. 2 is a collective perspective view of the connector.

Fig. 3 is an elevational view.

Fig. 4 is an end view taken on line 4—4 of Fig. 3.

I claim:

The ornamental design for an electrical connector, substantially as shown.

DONALD R. DE TAR.
